(57) **CLAIM**

The ornamental design for a container plumb with security bolt, as shown and described.

DESCRIPTION

FIG. 1 is a perspective view of a container plumb with security bolt showing our new design;

FIG. 2 is a top plan view thereof;

FIG. 3 is a bottom plan view thereof;

FIG. 4 is a front elevational view thereof;

FIG. 5 is a left side elevational view thereof;

FIG. 6 is a rear elevational view thereof; and,

FIG. 7 is a right side elevational view thereof.

The broken lines represent unclaimed portions and form no part of the claimed design.
